UNITED STATES PATENT OFFICE.

BERNARD O'REILLY, OF ROCHESTER, NEW YORK.

CORPSE-CARRIER.

1,240,359.

Specification of Letters Patent.

Patented Sept. 18, 1917.

Application filed April 27, 1917. Serial No. 165,002.

To all whom it may concern:

Be it known that I, BERNARD O'REILLY, a citizen of the United States, residing at Rochester, in the county of Monroe and State of New York, have invented certain new and useful Improvements in Corpse-Carriers, of which the following is a specification.

The object of this invention is to provide 10 a new and improved carrier for the use of undertakers when handling a corpse.

This and other objects of this invention will be fully illustrated in the drawings described in the specification and pointed out 15 in the claims at the end thereof.

In the accompanying drawings,

Figure 1 is a side elevation of the carrier.

Fig. 2 is a top plan view of the carrier.

Fig. 3 is a horizontal sectional view of 20 one of the joints in the frame of the carrier, the section being taken on the line of 3^x-3^x of Fig. 1.

Fig. 4 is a vertical sectional view of another joint in the frame of the carrier, the 25 section being taken on the line 4^x-4^x of Fig. 2.

Fig. 5 is a top plan view of one of the canvas sections which are folded up and suspended from the frame of the carrier to 30 form the sides, ends and bottom of the bag in which the corpse is carried.

Fig. 6 is an end elevation of the carrier.

Fig. 7 is a detail perspective view of one 35 of the hooks which are used to suspend the canvas bag from the frame of the carrier.

In the several figures of the drawings like reference numerals indicate like parts.

The carrier consists of a frame comprising the side rails 1 and 2 each of which is 40 made up of four sections 3, 4, 5, 6 and 3^A, 4^A, 5^A and 6^A respectively. The sections 3, 3^A and 6, 6^A are hinged to swing horizontally on the sections 4, 4^A and 5, 5^A respectively, and for this purpose the joints 7, 7^A and 8, 45 8^A are interposed between them. Each of these joints is made up of two knuckle members 9 and 10 which form one side of the joint and a third knuckle member 11 which projects between the knuckle members 9 and 10 and forms the other side of the joint. A bolt 12 passes through the center of all of these knuckle members to form the axis around which the knuckle members are adapted to rotate.

The sections 4, 5 and 4^A, 5^A are connected 55 together by means of the knuckle joints 13 and 14 which are made up of the knuckle members 15 and 16 with a bolt 17 passing through the center thereof around which the knuckle members are adapted to swing. 60 The joints 13 and 14 are provided so as to permit the side rails 1 and 2 to fold up in the middle thereof. A shoulder 18 is formed on top of each of the knuckle members 15 and 16, which shoulder forms a stop 65 to prevent the halves of each rail from folding up in the reverse direction and hold them in line with each other. The knuckle member 16 has a pair of notches 19 and 20 cut into the periphery thereof with which 70 the spring pressed pin 21 is adapted to engage. The pin 21 is mounted in the knuckle member 15 and has an enlarged end which is mounted to slide in the cylinder 23. A spring 24 is interposed between the enlarged 75 end 22 and the closed end of the cylinder 23 so as to normally force the pin 21 outwardly to engage either of the notches 19 and 20.

When the pin 21 engages the notch 19, the 80 two halves of the rail are locked together in line with each other and form one continuous rail. In order for the pin 21 to engage the notch 20, the two halves of the rail must be folded up to lie parallel to 85 each other in which position the pin 21 will engage the notch 20 and lock them in place in this position. A handle 24 is provided on the pin 21 which projects outwardly at right angles to it and passes through the 90 slot 25 in the knuckle member 15 as shown in Fig. 1. The handle 24 is used to operate the pin 21 and withdraw the pin from either of the notches 19 and 20. This is done 95 by moving the handle 24 rearwardly to force the enlarged end 22 of the pin 21 against the spring 24. This operation in turn releases the knuckle member 15 and 16 and permits them to rock around the bolt 17.

The sections 4 and 4^A and the sections 5 100 and 5^A are properly spaced apart by means of the crossbars 26 and 27. The sections 3 and 3^A and the sections 6 and 6^A are spaced apart by means of the crossbars 28 and 29 respectively to which they are hinged at 105 either end thereof.

The knuckle members 9, 10 and 11 of the joints 7, 7^A, 8 and 8^A are locked together by

means of the pin 30 which engages between the ratchet teeth 31 formed on the periphery of the knuckle member 10. The pin 30 is mounted to slide in the knuckle member 10 and is normally pressed outwardly by means of the spring 32 which is interposed between the enlarged end 33 and the end of the cylinder 34. A rod 35 is fastened to the rear end of the pin 30 which passes through the inside section of the rail to which the knuckle 11 is fastened. At the end of this rod is fastened the trigger handle 36 which projects out of the section and by means of which the pin 30 may be disengaged from the teeth 31 so that the sections can be swung around their joints.

In order to permit two of the end sections to shift simultaneously around their joints, the crossbars 28 and 29 are hinged to the sections 3, 3^A and 6, 6^A as shown at 37, 38, 39 and 40.

Supported from the frame 1 is the canvas bag 41 which consists of the flaps 42 and 43, each of which is formed by a central section 44 and the end sections 45 and 46. The lower part of each of the central sections is adapted to be folded along the dotted line 47 so as to form one-half of the bottom of the canvas bag 41. The end sections 45 and 46 are folded up on the dotted lines 48 and 49 to form one-half of the ends of the bag as shown in dotted line in Fig. 5.

The inner edge of each of the central sections and end sections of the flaps 42 and 43 are provided with a series of eyelets 50. A rope 51 is alternately threaded through the eyelets of each of the flaps starting at one end thereof so that the two flaps are held together at their ends and bottom to form the bag 41. The rope 51 is held in place at each end of the bag in any suitable manner or by means of a nut which is made large enough so as not to pass through the last one of the eyelets 51.

The bag 41 is suspended from the rails 1 and 2 by means of the hook 52, one of which is shown in Fig. 7. These hooks are sewed to the outer end of the flaps 42 and 43 as shown in Figs. 1 and 6 so that they can be hooked into the rails 1 and 2 and the crossbars 28 and 29 to support the bag below the frame 1.

As will be seen from an inspection of Figs. 1, 2, 5 and 6 the flaps 42 and 43 have triangular pieces of canvas 53 and 54 inserted into the central sections thereof. These pieces of canvas project outwardly from the bag 41 and are located below the joint 7, 7^A, 8 and 8^A when suspended from the rails 1 and 2 so as to permit the bag to swing with the ends of the frame without tearing the sides thereof.

Handles 55 are provided at each end of the side rails 1 and 2 by means of which the carrier is held by the persons handling

the carrier. The handles are mounted to slide in the ends of the rail which allows them to telescope into the inside of the end of the side rail when the carrier is not in use.

The carrier is operated as follows:

The side rails 1 and 2 are first extended and all of the sections of each rail are brought in line with each other and locked in this position by means of the pins 21 and 30 which engage the slots in the knuckle members 10 and 14 of the joints 7, 7^A, 8, 8^A, 13 and 14 respectively. The corpse is laid into the bag 41 which has been previously formed by the flaps 42 and 43 by alternately threading the rope 51 through the eyelets of each of the flaps to hold them together at the middle of the bag.

The bag 41 is then ready to be fastened to the frame 1 which is done by engaging the hooks 52 with the side rails 1 and 2 and the cross bars 28 and 29 as shown in Figs. 1, 2 and 6. The complete carrier with a corpse inside the bag 41 may then be lifted and carried to its destination.

If an abrupt corner in a small staircase is encountered and it is impossible to get through with the carrier in its extended form, either one or both of the end sections of the frame may be swung sidewise so as to conform to the passage way through which the corpse is to be carried. This is done by pulling out the pin 30 between the teeth 31 in the joints 7, 7^A or 8, 8^A by means of the trigger handles 36. This in turn unlocks the knuckle members of each of the joints and permits the end sections to be swung in the desired direction and at any angle required. When the frame of the carrier has been bent to allow it to pass the corner or other obstruction the trigger handles 36 are released so that the pins 30 again engage between the teeth 31 and lock the sections together in their bent form until the obstruction has been passed with the carrier. As soon as the carrier has passed the obstruction the sections of the frame may be swung back into their original position by again releasing the locking pin in the joints as above described and then shifting the sections until they are in line with each other, when they are again locked together as above pointed out.

When it is desired to remove the corpse from the bag 41 of the carrier the cord 51 is released on one end of the bag and pulled through all of the eyelets 50. This in turn opens the bag in the middle thereof and allows the flaps 42 and 43 to be pulled out underneath the corpse so that the carrier can be removed with the flaps suspended thereon while the corpse will remain at the point where it had been laid down.

I claim:

1. In a device of the character described, the combination of a pair of foldable side

rails, each of said side rails comprising a pair of intermediate sections and a pair of end sections, said end sections being mounted to swing horizontally on said intermediate sections, a crossbar connecting each of said corresponding sections of each of said side rails to properly space them apart from each other.

2. In a device of the character described
10 the combination of a pair of foldable side rails, crossbars connecting said side rails and forming a frame therewith, said frame being divided into an intermediate section and two end sections, said end sections being mounted
15 to swing horizontally on said intermediate section, means for locking all of side sections in line with one another.

3. In a device of the character described,
20 the combination of a pair of foldable side rails, crossbars connecting said side rails and forming a frame therewith, said frame being divided into an intermediate section and two end sections, said end sections being mounted to swing horizontally on said intermediate
25 section, means for locking all of side sections in line with one another, a canvas bag suspended from said frame.

4. In a device of the character described,
30 the combination of a pair of foldable side rails, crossbars connecting said side rails and forming a frame therewith, said frame being divided into an intermediate section and two end sections, said end sections being mounted to swing on said intermediate section, means
35 for locking all of said sections in line with one another, a pair of canvas sections suspended from said frame, a rope adapted to

hold said canvas sections together at their ends to form a bag below said frame.

5. In a device of the character described,
40 the combination of a foldable frame comprising end and intermediate sections, said end sections mounted to swing horizontally on said intermediate sections, a bag suspended from said intermediate and said end
45 sections, means for opening said bag in the center thereof.

6. In a device of the character described
45 the combination of a frame, said frame comprising side rails and cross rails, the ends
50 of each of said side rails being mounted to swing horizontally on the intermediate portion of said side rails, said cross rails connecting the ends of said side rails being pivotally mounted on said side rails to keep the
55 ends of said side rails parallel to each other while swinging horizontally on the intermediate portions of said side rails.

7. In a device of the character described
60 the combination of a frame, said frame comprising side rails and cross rails, the ends
65 of each of said side rails being mounted to swing horizontally on the intermediate portion of said side rails, joints between the ends and the intermediate portions of said side rails, a ratchet located at each of said joints to lock the ends and intermediate portions
70 of said side rails in line with each other, a spring pressed rod mounted on the ends of said side rails, said spring pressed rod being adapted to unlock said ratchets on said joints.

In testimony whereof I affix my signature.
BERNARD O'REILLY.
